UNITED STATES PATENT OFFICE.

JAMES TORSTEN SANDBERG, OF GOTTERNBOORG, SWEDEN.

PULLEY.

1,359,842.

Specification of Letters Patent. Patented Nov. 23, 1920.

Application filed December 24, 1919. Serial No. 347,245.

To all whom it may concern:

Be it known that I, JAMES TORSTEN SANDBERG, citizen of Sweden, residing at Gottenborg, in the county of Gottenborgs and 5 Bohus Län, Sweden, have invented certain new and useful Improvements in Pulleys, of which the following is a specification.

The present invention has reference generally to improvements in pulleys and more 10 particularly relates to a belt pulley having a detachable rim.

Briefly stated the invention consists of a body provided with a plate-shaped circumferential web portion which constitutes an 15 effective supporting surface for the rim and in addition includes means for detachably clamping the rim in position.

The invention is clearly illustrated in the accompanying drawing in which:—

20 Figure 1 is a side elevation of one form of the improved pulley.

Fig. 2 is an end elevation partly in section thereof.

Fig. 3 is a side elevation of the pulley according to another embodiment of the invention, and

Fig. 4 is the end view of the part shown in Fig. 3 partly in section.

Referring now more particularly to the 30 accompanying drawings there is provided spokes or arms 2 which are joined at their inner ends with the hub portion 3 and at their outer ends connected with the juncture and between oppositely inclined portions of 35 the annular web portions 5, 6. A rim 4 preferably of sheet iron is now arranged about the web portion 5 and has its adjacent terminals bent inwardly to form substantial hooks 10 which are positioned in a recess

40 11 in the web portion and engaged by a screw bolt 9 so as to be held against displacement. Diametrically opposite the recess 11 the web

portion is provided with another recess 12 which receives a counterbalancing weight and which weight in turn is retained by the 45 rim. As shown the hub portion of the pulley is preferably constructed in two sections which are clamped to the shaft by suitable means such as screwbolts 13.

In Figs. 1 and 2 the web portion has a 50 wave-like form whereas in Figs. 3 and 4 the web portion 6 is of a zigzag shape. However, in both cases the waves or zigzags are arranged radially to the rim 4.

As is apparent by employing the present 55 construction a larger carrying capacity is obtained by the pulley because of the fact that the web portion is actually broader than the web portion of other types of pulleys and this wider breadth is obtained without 60 increasing the weight.

It is believed that in view of the foregoing a further detailed description of the invention is entirely unnecessary. Likewise it is believed that the advantages of the invention 65 will be readily apparent.

Having thus fully described the invention what is claimed as new and desired to be secured by Letters Patent is:—

A belt pulley composed of a pair of sections each including a hub, spokes radiating therefrom and a wave-like web portion connected with the outer ends of the spokes, means for connecting the hub portions together, the web portions being provided with 70 opposed recesses, a rim surrounding the wave-like web portions and formed with in-turned ends receivable in one of the recesses, clamping means engaging the inturned ends of the rim and a counter-balancing weight 75 80 of the rim and a counter-balancing weight in the other recess and retained by the rim.

In testimony whereof I have affixed my signature.

JAMES TORSTEN SANDBERG.
